FLUID PRESSURE CONTROLLED SWITCH MECHANISM

Filed Dec. 19, 1947

UNITED STATES PATENT OFFICE

2,617,905

FLUID PRESSURE CONTROLLED SWITCH
MECHANISMMarcel Garancher, Chicago, Ill., assignor to
Stewart-Warner Corporation, Chicago, Ill., a
corporation of Virginia

Application December 19, 1947, Serial No. 792,676

2 Claims. (Cl. 200—83)

1

The present invention relates to compressors and more particularly to a control for a manually portable power operated air compressor which automatically stops the compressor when a predetermined pressure which may be varied is exceeded.

An object of the invention is the provision of an improved control means for a fluid compressor for automatically discontinuing the operation of the compressor when a predetermined pressure is exceeded, which control means is readily adjustable to vary the pressure at which operation of the compressor is discontinued.

Other objects of the invention will become apparent from the following description wherein reference is had to the accompanying drawings in which:

Fig. 1 is a side elevational view of a portion of a portable air compressor with the improved control in fragmentary section;

Fig. 2 is a fragmentary top plan view of the control by means of which operation of the compressor is regulated manually. This view may be considered as taken in the direction of the arrows on the line 3—3 of Fig. 1.

The control is substantially enclosed in a housing 182 which also encloses a portion 44 of the air compressor, the latter being enclosed by a housing 190 which is secured to a motor housing 194. The casting 44 is provided with a socket projection 198 for a caster 196 which projects through an opening 202 in the bottom of the housing 182. The compressor and motor assembly may also be supported by a pedestal 200 which may be generally U-shaped, and may be spot welded to the housing 194. The handle 204 may be spot welded to the housing 190.

The control means for stopping operation of the motor which drives the compressor whenever a predetermined pressure is exceeded at the discharge outlet 74 thereof, may be regulated manually to vary the pressure at which operation will be discontinued. Referring to Fig. 1 a passageway 124 is in communication with the discharge passage of the compressor and a diaphragm chamber 126 formed in a body casting 44. The outer end of this chamber is closed by a bellows type diaphragm 128 having peripheral edges that are engaged between the edge of the opening in the body casting forming the outer end of the diaphragm chamber and a peripheral flange 130 on a tubular plunger housing 132 secured over this opening by means of a plurality of cap screws, one of which is shown at 134. These cap screws are threaded into openings in

2

the casting and may be provided with lock washers so that the plunger housing and diaphragm will be firmly secured in position.

Slidable within the plunger housing 132 is a hollow plunger 136 which has a head adapted to be held in engagement with the outer side of the diaphragm 128 by a coil spring 138 reacting between the head of the plunger and a stop 140 carried adjacent the outer end of the plunger housing 132. This stop is provided with a fast thread such as the square thread shown which engages in a corresponding thread in the inner surface of the housing adjacent its outer end so that the stop may be adjusted longitudinally of the housing for varying the tension in the spring 138 and need be turned through only a relatively small angle to secure a large adjustment.

It is rotated for regulating the tension of the spring by means of a knob 142 having stem 144 operatively connected to the stop by any suitable means. This knob 142 projects through and is rotatably carried in a dial plate 146 set in an enlarged outer end flange 148 on the plunger housing 132. A C spring 150 is engaged in a peripheral groove on a reduced portion 152 of the knob extending through the dial plate 146 (Fig. 2) in a position to engage the back of the plate and thus hold the knob in position but yet allow free rotation of the same. The knob may be provided with an indicator 154 which sweeps over graduations 156 on the dial for indicating, for example, air pressure in pounds per square inch at which operation of the compressor will automatically be discontinued if the indicator is moved to that point.

From the above description it will be apparent that deflection of the diaphragm 128, due to an increase in the pressure of the air in chamber 126, will force the plunger 136 outwardly in the plunger housing in opposition to the biasing force of spring 138. The magnitude of the pressure required to move the plunger can of course be adjusted by turning knob 142, thereby advancing or retracting stop 140 and increasing or decreasing the tension in spring 138.

Movement of the plunger in this manner opens and closes a snap switch 158 of conventional construction through a semi-spherical abutment 160 carried adjacent the outer end of the plunger and projecting into a slot 162 in the wall of the plunger housing. The switch has a button or pin 164 for closing the same projecting into the path of the abutment, and this pin is depressed to close the switch when the abutment engages the same, as shown in Fig. 1. Energization of the motor 10

is controlled by the switch and as long as abutment 160 remains in contact with the pin 164, the motor circuit will be energized.

In order to permit manual control of the switch 158, it is mounted so that it may be bodily oscillated to carry the pin 164 into and out of the path of movement of the abutment 160. As best seen in Fig. 1, an extended portion of the flange 130 on the plunger housing forms a base 166 to which the switch is secured by means of a shouldered screw 168 extending through the base and switch, and threaded into the inner end of a stem 170 which projects through the outer end flange 148 on the plunger housing. A washer 172 is interposed between the back of the switch and the base 166 and is engaged by the shoulder on the screw 168 so that the switch may be rocked to carry its pin into or out of the path of movement of the abutment 160 by manipulating the projecting end of stem 170.

When the compressor is in use it is supported upon the floor by means of a caster 196 shown in Fig. 1 which is secured in a depending boss 198 on the bottom side of the compressor body casting 44 and a transversely extending foot 290 adjacent the rear end of the compressor. The foot may be made from a single strap of metal formed to provide a flat part for resting on the floor, and a pair of upwardly extending arms by means of which the foot is secured to the sides of the rear end section 194 of the housing by spot welding or other means of securing. The caster 196 projects through an opening 292 in the bottom side of the forward section 182 of the housing so that it is in position to contact the floor and thus allow the compressor to be moved in the manner of a wheel barrow, or it may be carried by means of the handle 294.

In operating the compressor the manually adjustable knob 142 is first set at the pressure which it is desired to develop at the discharge end of the conduit 78. The stem 170 may then be oscillated in the proper direction to move the pin 164 on the snap switch 158 into engagement with the abutment 160 on the plunger 136, thus energizing the motor and causing the compressor to be operated. The snap switch 158 is connected in the motor energizing circuit.

Some of the air discharged by the air compressor flows through passageway 124 into the diaphragm chamber 126, and as the pressure in this chamber increases, it will finally reach the point where the diaphragm 128 is moved upwardly, from the position shown in Fig. 1, thus disengaging abutment 160 from pins 164 and 55 allowing the snap switch 158 to open, thereby discontinuing operation of the motor. At any time it is desired the compressor can of course be shut down by operating the stem 170 to rock the snap switch body in a direction to move its pin 164 from the path of movement of the abutment 160 on the diaphragm plunger.

While I have shown and described a preferred embodiment of my invention, it will be apparent that numerous variations and modifications thereof may be made without departing from the underlying principles of the invention. I,

therefore, desire, by the following claims, to include within the scope of the invention all such variations and modifications by which substantially the results of my invention may be obtained through the use of substantially the same or equivalent means.

I claim:

1. A fluid pressure operated control comprising body structure having a diaphragm chamber formed therein adapted to be connected to a source of fluid under pressure, diaphragm means in said chamber movable in response to variations in the pressure of the fluid in said chamber, means forming a cylinder opposite said diaphragm chamber, a plunger slidable in said cylinder and adapted to be moved in one direction by said diaphragm means, means for biasing said plunger in opposition to said diaphragm means, a normally open switch having a projecting operating part and means on said plunger adapted to contact the operating part of said switch to close the latter when said plunger moves in response to a reduction in pressure in the chamber below a predetermined value, and manually operable means for moving said switch bodily to a position at which said means on said plunger is ineffective to close the switch.
2. A fluid pressure operated control comprising body structure having a diaphragm chamber formed therein adapted to be connected to a source of fluid under pressure, diaphragm means in said chamber movable in response to variations in the pressure of the fluid in said chamber, means forming a cylinder opposite said diaphragm chamber, a plunger slidable in said cylinder and adapted to be moved in one direction by said diaphragm means, adjustable means in said cylinder for biasing said plunger in the opposite direction, a switch biased to open position having a projecting operating finger and a projecting part on said plunger adapted to contact said finger thereby to close the switch when said plunger moves in response to a reduction in pressure in said chamber below a predetermined value, and manually operable means for moving said switch bodily to remove said projecting finger from the path of movement of said projecting plunger part thereby to render said finger and said plunger part ineffective to close the switch.
